UNITED STATES PATENT OFFICE.

WILLIAM A. GEIGER, OF CHICAGO, ILLINOIS, ASSIGNOR, BY MESNE ASSIGNMENTS, TO
W. H. MINER, INC., A CORPORATION OF DELAWARE.

ANTIFRICTION BEARING.

Application filed September 20, 1924. Serial No. 738,745.

This invention relates to improvements in anti-friction bearings.

One object of the invention is to provide a simple, practical and relatively inexpensive 5 roller bearing, especially adapted for railway car side bearings, in which the parts are so arranged that the anti-friction element is automatically returned to normal centered position when free from load.

10 Another object of the invention is to provide a bearing of this character, including a mounting adapted to be disposed upon the truck bolster of a railway car, and a roller adapted to have rolling engagement with 15 said mounting during a portion of the relative movement of the truck and body bolsters, and thereafter be supported for unlimited rotation about its axis, in conjunction with counterweights cooperating with 20 said roller which serve to automatically return the roller to centered position when the load is removed therefrom.

Another object of the invention is to provide a shiftable connection between the 25 counterweights and the roller so that when the roller moves to either side of centered position, the connection operates to concentrate the return pull on the roller at the most effective points thereon, thereby increasing 30 the centering capacity of the counterweights.

Other and further objects of the invention will more fully and clearly appear from the description and claim hereinafter following.

35 In the drawing forming a part of this specification, Figure 1 is a vertical, sectional view taken through the ends of the body and truck bolsters of a railway car, showing my invention in connection therewith. And Figure 2 is a sectional view of the invention on the line 2—2 of Figure 1.

Referring to the drawings, A indicates the underside of a body bolster, and B the upper side of the corresponding truck bolster of a 45 railway car. My improved side bearing is shown as applied to the truck bolster and comprises, broadly, a housing C; horizontally spaced bearing seats D; counterweight guides E; an anti-friction element F; and 50 counterweights G.

The housing C is preferably a hollow shell provided with curved end walls 3, and flanges 4 adapted to be secured to a bearing plate 5, which forms the bottom of the housing, by means of rivets 6, the bearing plate

in turn being secured to the truck bolster B by means of suitable rivets 7. The opposite side walls 8 of the housing C are offset to provide the horizontally spaced, arcuate bearing seats D, and further offset to provide the guides E at either side of the housing, each of such guides preferably comprising a relatively restricted portion including vertically disposed, spaced side walls 9, which diverge upwardly as indicated at 10, 65 and have their upper portions merged to provide the top wall 11. The side walls of the housing are also provided at their upper edges with overhanging retaining flanges 12, as shown. 70

The anti-friction roller F is disposed in the housing and adapted to have rolling movement upon the bearing plate 5, and such roller is provided with relatively large trunnions 13 at its ends. The trunnions 75 13 are adapted for operative engagement with the bearing seats D when the roller has moved a sufficient distance to either side of centered position, the bearing seats D being so disposed that when the trunnions 13 engage the same, the roller is slightly elevated and supported for unlimited rotation about its axis. 80

The outer ends of the trunnions 13 are preferably provided with circular sockets 85 14 each of which is adapted for the reception of a relatively small stud 15, formed on the upper portion of each counterweight G, which arrangement permits shifting of the bearing points of the studs 15 relative 90 to the walls of the sockets 14. The counterweights G are disposed within the guides E, and are preferably substantially pear-shaped, each including an enlarged lower rounded portion 16, which slidably fits between the walls 9 of the related guide E, and a reduced portion 17 adapted to have swinging movements within the diverging walls 10 of the related guide, during operation of the roller. 95 100

The operation of the device is as follows, assuming that the roller is moving toward the right as shown in dotted lines in Figure 1. During the normal position of the various members of the anti-friction bearing, the 105 counterweights G through the influence of gravity retain the anti-friction element F in centered position in the housing. During the travel of the car in rounding a curve, the bolsters A and B have relative move- 110

ment, and the bolster A engages the anti-friction element F causing rolling of the same upon the bearing plate 5 through a limited distance, and upon further movement of the bolsters with respect to each other, the trunnions 13 will ride upon the bearing seats provided therefor, which will result in a slight elevation of the roller, at which time the trunnions will support the roller for unlimited rotation about its axis. During the movement of the roller F to the position just described, the counterweights G are carried therewith, and by reason of engagement thereof with the adjacent walls 15 of the guides E, such counterweights are vertically displaced, and when the load exerted by the engagement of the bolsters is removed, the counterweights G will return the roller to centered position through the influence of gravity. During the movement 20 of the roller to the position where the trunnions engage the seats, the studs 15 of the counterweights shift their bearing points relatively to the walls of the sockets 14 which results in the return pull of the counterweights being concentrated at the most effective points on the roller, in contradistinction to a distribution of the lines of force over a greater area, were the bearing snugly 25 fitting, whereby the centering capacity of the counterweights is appreciably increased.

While I have herein shown and described what I now consider the preferred manner 30 of carrying out my invention, the same is

merely illustrative, and I contemplate all changes and modifications that come within the scope of the claim appended hereto.

I claim:

In an anti-friction bearing, the combination with a retaining member adapted to be secured to a bolster and having a bearing surface associated therewith and provided also with bearing seats adjacent its ends; of an anti-friction element, the peripheral 45 surface of which is adapted to have rolling engagement with said bearing surface for limited amounts of travel to either side of central normal position, said element being provided with trunnions adapted to engage 50 said bearing seats at either end of its rolling movement and thereafter permit rotation of said element about the axis of said trunnions; and gravity-influenced combined counter-weight and centering means 55 movably attached to said element, said retaining member having guide surfaces co-operable with said centering means and so arranged that, as said element is actuated to either side of its central normal position, said centering means will be elevated and when said element is relieved of load, said centering means will return said element to central normal position from any rolling or rotative operative position that said element may 60 assume.

In witness that I claim the foregoing I have hereunto subscribed my name this 16th day of September 1924.

WILLIAM A. GEIGER.
